CLAIM

We claim the ornamental design for dual direction e-track connector mounts, as shown and described.

DESCRIPTION

FIG. 1 is a front perspective view of a dual direction e-track connector mount of the present invention.

FIG. 2 is a left side elevation view of the dual direction e-track connector mount of FIG. 1.

FIG. 3 is a right side elevation view of the dual direction e-track connector mount of FIG. 1.

FIG. 4 is a bottom plan view of the dual direction e-track connector mount of FIG. 1.

FIG. 5 is a top plan view of the dual direction e-track connector mount of FIG. 1.

FIG. 6 is a front elevation view of the dual direction e-track connector mount of FIG. 1; and,

FIG. 7 is a rear elevation view of the dual direction e-track connector mount of FIG. 1.

The broken lines depict portions of the article that form no part of the claimed design.
